UNITED STATES PATENT OFFICE.

WILBUR SCHUTTE, OF CHICAGO, ILLINOIS.

ROTARY VALVE.

1,160,830.

Specification of Letters Patent. Patented Nov. 16, 1915.

Application filed January 12, 1915. Serial No. 1,809.

To all whom it may concern:

Be it known that I, WILBUR SCHUTTE, a citizen of the United States, and a resident of the city of Chicago, county of Cook, and State of Illinois, have invented certain new and useful Improvements in Rotary Valves, of which the following is a specification.

My invention relates to improvements in rotary valves for internal combustion engines, the present application being in part a division of my pending application, Serial No. 827,069, filed March 25th, 1914, for rotary valves for internal combustion engines.

15 The object of this invention is the production of a rotary valve mechanism in which the valve proper will be so connected with the driving means coöperating therewith as to permit of ready and easy disconnection of the valve from said driving mechanism, and replacement thereof without disturbing the timing of the valve relative to the reciprocations of the pistons of the engine.

20 25 A further object is the production of valve mechanism as mentioned which will be of simple construction and efficient in operation.

Other objects will appear hereinafter. 30 With these objects in view, the invention consists in the combinations and arrangements of parts hereinafter described and claimed.

The invention will be best understood by 35 reference to the accompanying drawings forming a part of this specification, and in which,

Figure 1 is a top plan view of a valve mechanism embodying my invention, the 40 same being shown applied to an internal combustion engine, Figs. 2 and 3 are elevations of the opposite ends of the construction shown in Fig. 1, Fig. 4 is a central vertical section of the construction shown in 45 Fig. 1, and Fig. 5 is an end elevation of the rotary valve detached.

The preferred form of construction as 50 illustrated in the drawings is applied to an internal combustion engine consisting of cylinders 1, the upper ends of which are closed by a plate 2. Said plate is formed with inlet and exhaust ports which are controlled by the valve mechanism in the manner clearly set forth in my parent application, 55 above referred to. This valve mechanism comprises a cylindrical housing 3 which is

secured by bolts 4 to the upper ends of cylinders 1. One end of said housing is closed by a head consisting of two sections 5 and 5' which are secured together by screws 5", 60 the opposite end of said housing being closed by a head 6. The heads 5—5' and 6 are secured to the respective ends of said housing by bolts 7 and 8 respectively. The heads 5—5' and 6 are also supported on 65 outwardly projecting flanges 9 and 10 respectively, which are provided at the upper ends of cylinders 1, being fastened to said flanges by means of bolts 11 and 12 respectively.

70 Rotatably mounted within the housing 3 is a valve 13 of substantially cylindrical form and adapted, in operation, to control the inlet and exhaust ports communicating with the upper ends of the cylinders 1. The 75 construction and operation of the valve 13 so far as the same controls the inlet and exhaust of cylinders 1 forms no part of this invention, this construction being the subject matter of my parent application, above 80 referred to. Hence, the detail construction of said valve, or its operation, will not be gone into in this case. It is desired to point out, however, that the axial passage 14 formed through the valve 13 and which constitutes the exhaust manifold of the valve 85 communicates at one end with a passage 15 formed in the head 6 and which in turn communicates with an exhaust pipe 16 secured to and extending from the flange 10.

90 Rotation of the valve 13 is effected by means of a bevel gear 17 which is rotatably mounted upon a supporting stud 18 formed upon the inner side of the member 5. Ball bearings 19 are interposed between the stud 95 18 and the hub of said gear to alleviate friction. Formed upon and projecting outwardly from the adjacent end of valve 13 is a plurality of pins or studs 20 which readily engage correspondingly positioned recesses 21 formed for the reception thereof in the adjacent side of gear 17. With this arrangement, it will be seen that an operative connection between said valve and gear is established which permits of disengagement of said valve from said gear upon sliding of said valve longitudinally from said gear. The gear 17 meshes with a pinion 22 fixed to the upper end of a shaft 23 which is operatively connected at its lower end 110 with the crank shaft of the engine or other driving element for effecting rotation of the

valve body at a speed properly timed with the reciprocations of the pistons of the cylinders.

With the construction set forth then, it will be seen that, if it is desired to remove the valve and its housing for repairing, cleaning or renewing said valve, it is only necessary to remove the bolts 4, 7 and 12. When this is done, the valve housing and head 6 will be disconnected from the engine so as to permit of longitudinal sliding of the parts from the head 5-5' so as to effect disengagement of the studs 20 of the valve from the gear 17. When said parts are removed, the head 5-5' will constitute a housing or support for the gear 17 holding the same in fixed relation with the engine cylinders and therefore maintaining the proper timing of the valve so that upon remounting of the latter, the proper timing will be secured without any adjustment. This is, of course, of great advantage since without the independent supporting means for the valve driving gear, upon demounting of the valve, the timing thereof would be disturbed and interfered with which would subsequently result in considerable loss of time in readjusting the valve to secure the proper timing thereof.

30 By connecting the exhaust pipe 16 with the flange 10, instead of directly with the head 6, the necessity of disconnecting the head 6 from said valve, as would be the case when demounting the valve, were the other construction used, is obviated.

While I have illustrated and described the preferred form of construction for carrying my invention into effect, this is capable of variation and modification without departing from the spirit of the invention. I, therefore do not wish to be limited to the precise details of construction set forth, but desire to avail myself of such variations and modifications as come within the scope of the appended claims.

Having described my invention what I claim as new and desire to secure by Letters Patent is:

1. The combination with an internal combustion engine, of valve mechanism arranged for coöperation with said engine, said valve mechanism comprising a housing removably mounted on said engine; a valve rotatably mounted in said housing; a rotatable driving member arranged at one end of said housing; a support for said driving member independently supported on said engine; and a releasable connection between said valve and said driving member, substantially as described.

2. The combination with an internal combustion engine, of valve mechanism arranged for coöperation with said engine, said valve mechanism comprising a housing removably mounted on said engine; a valve

rotatably mounted in said housing; a rotatable driving member arranged at one end of said housing; a support for said driving member independently supported on said engine; and a releasable connection between 70 said valve and said driving member permitting of disengagement of said valve from said driving member upon longitudinal sliding of said valve, substantially as described.

3. The combination with an internal combustion engine, of valve mechanism arranged for coöperation with said engine, said valve mechanism comprising a housing removably mounted on said engine; a valve rotatably mounted in said housing; a rotatable driving member arranged at one end of said housing; a supporting member for 80 rotatably supporting said driving member, said supporting member being supported on the engine independently of said valve housing; and pins on one end of said valve 85 housing; and pins on one end of said valve releasably engaging recesses provided in said driving member for operatively connecting said parts so as to permit of disengagement of said valve from said driving member 90 upon longitudinal movement of said valve from said driving member, substantially as described.

4. The combination with an internal combustion engine of valve mechanism arranged 95 for coöperation with said engine, said valve mechanism comprising a housing removably mounted on said engine; a valve rotatably mounted in said housing; a driving gear arranged at one end of said housing; a supporting member for rotatably supporting said gear, said supporting member being supported on the engine independently of said valve housing; and projections on one 100 end of said valve releasably engaging recesses provided in said gear for operatively connecting said parts so as to permit of disengagement of said valve from said gear upon longitudinal movement of said valve 105 from said gear, substantially as described. 110

5. In a valve mechanism, the combination of a housing; a valve rotatably mounted in said housing; a rotary member arranged at one end of said valve for driving the same; a two-part housing in which said driving 115 member is rotatably mounted, said last mentioned housing being supported independently of said valve housing; means on one end of said valve projecting longitudinally therefrom loosely engaging recesses, provided in the adjacent side of said driving member for operatively connecting said driving member and said valve so as to permit of engagement or disengagement of said valve relative to said driving member upon longitudinal sliding of said valve; and means for releasably holding said valve against relative longitudinal movement, substantially as described. 125

6. The combination with an internal com- 130

bustion engine having an exhaust pipe supported thereon; a valve mechanism arranged for controlling the inlet and exhaust of said engine, said mechanism comprising
5 a housing removably mounted on said engine; a valve rotatably mounted in said housing; driving mechanism for said valve arranged at one end of said housing and having independent support on said engine;
10 and a releasable operative connection between one end of said valve and said driving mechanism, there being an opening formed in the opposite end of said housing establishing communication between said valve
15 and said exhaust pipe, substantially as described.

7. The combination with an internal combustion engine having an exhaust pipe supported at one side thereof; a valve mechanism arranged for controlling the inlet and exhaust of said engine, said mechanism comprising a housing removably mounted on said engine; a valve rotatably mounted in

said housing; driving mechanism for said valve arranged at one end of said housing 25 and having independent support on said engine; a releasable operative connection between one end of said valve and said driving mechanism, permitting of release of said valve from said driving mechanism 30 upon longitudinal sliding of said valve from said driving mechanism, said exhaust pipe communicating with the under side of said housing at the opposite end thereof; and a passage formed in said end of said housing 35 establishing communication between said valve and said exhaust pipe, substantially as described.

In testimony whereof I have signed my name to this specification in the presence of 40 two subscribing witnesses.

WILBUR SCHUTTE.
